Attorney.

UNITED STATES PATENT OFFICE.

HUGO LENTZ, OF HALENSEE, NEAR BERLIN, GERMANY.

NOZZLE-CASING FOR STEAM-TURBINES.

1,000,928.

Specification of Letters Patent. Patented Aug. 15, 1911.

Application filed April 1, 1909. Serial No. 487,245.

To all whom it may concern:

Be it known that I, HUGO LENTZ, a subject of the German Emperor, residing at Halensee, near Berlin, Germany, have invented a new and useful Nozzle-Casing for Steam-Turbines; and I do hereby declare the following to be a full, clear, and exact description of the same.

The present invention relates, particularly, to improvements in steam-supply casings terminating in nozzles for directing steam against the blades of turbine wheels, and the object of the invention is to control the supply of the steam and to compensate for or prevent temperature variations in the steam.

In steam turbines, up to the present time, it has been customary to conduct the supplied steam through a ring-like channel. The casing invented by me differs from prior structures in having two ring-like channels, separated by a wall common to both, one ring for leading steam from the boiler, superheater (or other source of steam supply) to a throttle-valve or control valve, and the other channel leading steam from said valve to one or more discharge nozzles.

Referring to the accompanying drawings: Figure 1 is a vertical section through the casing (on the line 1—1 of Fig. 2) and through the valve-casing and turbine wheel; and Fig. 2 is a front view (at the line 2—2 of Fig. 1) of the casing, the valve-casing and the turbine wheel having been removed.

35 *a* indicates a casing, which may be of a cast metallic ring, provided with the inner and outer concentric channels *b* and *c* separated by the parti-wall or common wall, *d*. The outer channel, *b* is supplied, at *e*, with steam from a superheater or from a boiler, and such steam, divided to pass around the inner channel and to heat the common wall *d*, reaches (by means of the passage *f*) the valve-casing *g*, and the throttle-valve or control-valve *h*, from whence (by means of passage *i*) the steam reaches the inner ring-like channel *c*, and then passes, by way of the nozzle-ring (*k*), and the nozzle or nozzles thereto connected, to the pressure and guide-blades, to cause rotation of the wheel *l*.

The construction provided by me is not only symmetrical, but is adapted to be easily made, set up, or repaired. In use, the incoming (or supplied) fresh, or live, steam constantly heats the parti-wall *d*, with the result that, in the channel *c*, temperature variations are compensated for, or practically prevented, even under great variations of load.

What I claim is:

1. A nozzle casing for steam turbines, comprising a body portion provided with continuous, uninterrupted inner and outer concentric channels having a common, heat-transferring wall therebetween, a passage supplying live steam to the outer channel, and a passage connecting said concentric channels in series, said channel entering the inner channel at a point diametrically opposite to the point of entrance of the channel for the live steam.

2. In a steam turbine, the combination of a casing provided with continuous outer and inner concentric channels, having a common heat transferring wall therebetween; a live steam passage for leading live steam to the outer channel, and a passage connecting said channels in series and communicating therewith at a point diametrically opposite to the point of entrance of the live steam passage; a controlling valve in said connecting passage; and a governor for operating the controlling valve.

3. A nozzle casing for steam turbines having continuous concentric channels having a common, heat-transferring wall therebetween, a connecting passage connecting the channels in series, and live steam passage leading steam to one channel at a point diametrically opposite to the entrance of the connecting passage to the other channel; and a controlling valve in the connecting passage.

In testimony whereof, I have signed my name to this specification in the presence of two subscribing witnesses.

HUGO LENTZ.

Witnesses:
